assignors, by mesne assignments, to Gardner-Denver
Company, a corporation of Delaware

Application October 29, 1953, Serial No. 27,378

Term of patent 14 years

(Cl. D54—14)

Fig. 1 is a side elevation of an electric tool for applying conductors to terminals, embodying our new design.

Fig. 2 is a rear elevation of the design illustrated in Fig. 1.

Fig. 3 is a top plan view of the tool illustrated in Figs. 1 and 2.

Fig. 4 is a perspective view of the tool illustrated in Figs. 1, 2 and 3.

An elevational view of the opposite side of the tool to that shown in Fig. 1 of the drawing would show such side to be substantially of the same appearance as the side shown in Fig. 1.

We claim:

The ornamental design for an electric tool for applying conductors to terminals, as shown and described.
